UNITED STATES PATENT OFFICE.

ALBERT A. HUSEBY, OF CHICAGO, ILLINOIS.

PEDAL-ACTION FOR PIANOS.

1,085,915.

Specification of Letters Patent.

Patented Feb. 3, 1914.

Application filed March 1, 1913. Serial No. 751,418.

To all whom it may concern:

Be it known that I, ALBERT A. HUSEBY, a citizen of the United States, residing at Chicago, in the county of Cook and State of Illinois, have invented certain new and useful Improvements in Pedal-Actions for Pianos, of which the following is a specification.

This invention relates to pedal actions for pianos and like musical instruments employing expression-pedals, and has for its object to provide a simplified and improved pedal action of that type which employs one or more horizontal rock-shafts between the 15 pedals and the lifter-rods actuated thereby and which affords variable movements of the hammer-rail by means of two pedals acting through a single rock-shaft and lifter-rod.

20 My invention, its construction, mode of action, and advantages, will all be readily understood when considered in connection with the accompanying drawing illustrating one practical embodiment thereof, in 25 which—

Figure 1 is a top plan view of the lower portion of a piano case showing my improved pedal action applied thereto; and Fig. 2 is an end elevation, partly in section, 30 as viewed from the right of Fig. 1.

Referring to the drawing, 5 designates the damper pedal and 6 and 7 soft pedals which operate in a well known manner to shift the hammer-rail toward the strings reducing 35 the length of hammer stroke. These pedals are pivoted at 8, 9 and 10, respectively, in and between bearing-blocks 11. Journaled in bearing-blocks 12 is a rock-shaft 13 which, at one end, has a forwardly-bent arm 14 terminating in a right-angle bend 15 that directly overlies the inner end of the damper pedal 5. The other end of the rock-shaft has a forwardly extending arm 16 that engages the lower end of the lifter-rod 17 40 of the dampers. Also journaled in the bearing-blocks 12 parallel with the rock-shaft 13 is another similar rock-shaft 18 having at one end a forwardly-bent arm 19 terminating in a right-angle bend 20 that 45 overlies the inner ends of both of the soft 50 pedals 6 and 7. The other end of rock-shaft 18 has a forwardly-bent arm 21 to which is connected the lower end of the lifter-rod 22 of the hammer-rail.

55 It will be observed that the laterally ex-

tending arms of the rock-shafts 13 and 18 which engage the pedals and the lifter-rods, respectively, are both on the same side of each rock-shaft, so that the combined weight of these arms, together with the damper 60 springs and the weights of the hammer-rail and lifter-rods 17 and 22 are amply sufficient to normally maintain the pedals 5, 6 and 7 in elevated position without requiring the use of springs for this purpose. It will 65 further be observed that the pivots 9 and 10 of the pedals 6 and 7, respectively, are relatively offset, thus affording different lengths of lever arms formed by the inner portions of said pedals, whereby the pedal 6 throws the hammer-rail closer to the strings than the pedal 7, so that, while both the pedals 6 and 7 are soft pedals, they differ in respect to the degree of sound-softening effects 70 75 which they produce.

Bent wire springs 23 and 24 overlie the inner portions of the pedals 6 and 7, respectively, and are anchored at their ends in the bearing-blocks 11. The purpose of these springs is simply to prevent either of the 80 85 pedals 6 and 7 from dropping when the other is actuated.

I claim—

1. In a piano pedal action, the combination with a pair of pedals pivoted between 85 their respective ends, and a lifter-rod, of a rock-shaft having an arm overlying and engaging the inner ends of said pedals and another arm engaging said lifter-rod, the pivots of said pedals being at different distances from the respective points of engagement of the inner ends of said pedals with said arm.

2. In a piano pedal action, the combination with a pair of pedals pivoted between 95 their respective ends, and a lifter-rod, of a rock-shaft having at one end an arm formed with a terminal portion lying parallel with the rock-shaft and resting upon the inner ends of said pedals and another arm on the 100 same side of said rock-shaft engaging said lifter-rod, the pivots of said pedals being at different distances from the respective points of engagement of the inner ends of said 105 pedals with the said terminal portion of said arm.

ALBERT A. HUSEBY.
